(57) **CLAIM**

I claim the ornamental design for the collapsible bowl, as shown and described.

DESCRIPTION

FIG. 1 is a perspective view of the collapsible bowl, showing my new design;

FIG. 2 is a top view of the collapsible bowl;

FIG. 3 is a front view of the collapsible bowl, the back view being identical;

FIG. 4 is a left side view of the collapsible bowl, the right side view being identical; and,

FIG. 5 is a bottom view of the collapsible bowl.
